US012018489B2

(12) **United States Patent**
Majocka et al.

(10) **Patent No.:** US 12,018,489 B2
(45) **Date of Patent:** Jun. 25, 2024

(54) **DOMED ROOF DRAIN STRAINER
ASSEMBLY**

(71) Applicant: **Zurn Industries, LLC**, Milwaukee, WI (US)

(72) Inventors: **Christopher Alan Majocka**, Erie, PA (US); **Matthew Curtis Henderson**, Girard, PA (US); **Christopher Joseph Say**, Waterford, PA (US)

(73) Assignee: **ZURN WATER, LLC**, Milwaukee, WI (US)

(*) Notice: Subject to any disclaimer, the term of this patent is extended or adjusted under 35 U.S.C. 154(b) by 0 days.

(21) Appl. No.: **17/192,688**

(22) Filed: **Mar. 4, 2021**

(65) **Prior Publication Data**

US 2021/0317666 A1 Oct. 14, 2021

Related U.S. Application Data

(57) **ABSTRACT**

A roof drain including a base defining a channel and an axis, a gravel guard coupled to the base and including a plurality of teeth, where the gravel guard defines a plurality of gullets between the teeth, and a dome coupled to the base, where the dome includes a plurality of ribs, where the ribs define a plurality of gaps therebetween, and where each gap is radially aligned with a corresponding gullet.

DOMED ROOF DRAIN STRAINER
ASSEMBLYCROSS-REFERENCE TO RELATED
APPLICATIONS

The present application claims priority to U.S. Provisional Patent Application No. 63/009,894, filed Apr. 14, 2020. The entire contents of which are hereby incorporated by reference.

FIELD

The embodiments described herein relate to a roof drain, and more particularly, to a roof drain having improved drainage and flow characteristics.

BACKGROUND

Commercial buildings are typically constructed with flat or near flat roofs. Because these building do not have much of a pitch, the collection of water on the roof surface from rain or melting snow can present serious structural loads that could result in collapse. To avoid this possibility, most commercial and industrial building standards require that roofs of this type include drains positioned at locations that ensure the water accumulated thereon can be removed in a timely manner.

SUMMARY

In one embodiment, a roof drain including a base defining a channel and an axis, a gravel guard coupled to the base and including a plurality of teeth, where the gravel guard defines a plurality of guttels between the teeth, and a dome coupled to the base, where the dome includes a plurality of ribs, where the ribs define a plurality of gaps therebetween, and where each gap is radially aligned with a corresponding gullet.

In another embodiment, a roof drain including a base defining an axis, the base having a throat portion and a flange portion extending radially outwardly from the throat portion, where the throat portion at least partially defines a channel therethrough having an outlet, and where the flange portion includes an outer edge and a top plane, a gravel guard coupled to the base and including a plurality of teeth, where the gravel guard defines a plurality of guttels, and where at least a portion of each gullet is positioned axially below the top plane, and a dome coupled to the base.

In another embodiment, a roof drain including a base at least partially defining a channel therethrough, where the channel includes an inlet and an outlet defining an outlet diameter, and where the base defines a top plane, a gravel guard coupled to the base and including a plurality of teeth and a plurality of guttels positioned between adjacent teeth, and a dome coupled to the base, where the roof drain is configured to flow between 75 GPM and 150 GPM through the channel at 1" of head pressure measured relative to the top plane.

BRIEF DESCRIPTION OF THE DRAWINGS

FIG. 1 is a perspective view of drain of the present invention.

FIG. 2 is a side view of the drain of FIG. 1.

FIG. 3 is a top view of the drain of FIG. 1.

FIG. 4 is a section view taken along line 4-4 of FIG. 3.

2

FIG. 5 is a detailed section view taken from FIG. 4.

FIG. 6 is a perspective view of a base from the drain of FIG. 1.

FIG. 7 is a section view taken along line 7-7 of FIG. 6.

FIG. 8 is a detailed section view taken from FIG. 7.

FIG. 9 is a perspective view of a dome from the drain of FIG. 1.

FIG. 10 is a top view of the dome of FIG. 9.

FIG. 11 is a side view of the dome of FIG. 9.

FIG. 12 is a perspective view of a gravel ring of the drain of FIG. 1.

FIG. 13 is a top view of the gravel ring of FIG. 12.

FIG. 14 is a detailed top view taken from FIG. 13.

FIG. 15 is another embodiment of a gravel ring.

FIG. 16 is a top view of the gravel ring of FIG. 15.

FIG. 17 is a detailed top view taken from FIG. 16.

FIG. 18 is a perspective view of another embodiment of a gravel ring.

FIG. 19 is a top view of the gravel ring of FIG. 18.

FIG. 20 is a detailed top view taken from FIG. 19.

FIG. 21 is a perspective view of another embodiment of a dome.

FIG. 22 is a perspective view of another embodiment of a base.

FIGS. 23-26 illustrate alternative embodiments of the crossbars of the dome.

FIG. 27 illustrates a prior art embodiment of a roof drain installed on a roof.

FIGS. 28-30 illustrate flow data generally corresponding to an embodiment of the roof drain.

FIGS. 31-34 illustrate another embodiment of the roof drain.

FIGS. 35-36 illustrate flow data generally corresponding to an embodiment of the roof drain.

DETAILED DESCRIPTION

Before any embodiments of the invention are explained in detail, it is to be understood that the invention is not limited in its application to the details of construction and the arrangement of components set forth in the following description or illustrated in the following drawings. The invention is capable of other embodiments and of being practiced or of being carried out in various ways. Also, it is to be understood that the phraseology and terminology used herein is for the purpose of description and should not be regarded as limiting.

FIG. 27 illustrates a prior art embodiment of a roof drain 5000 mounted to a roof 5100 with a roof membrane 5104 to produce a finished surface 5108. The roof drain 5000 includes a base 5004, a dome 5008, and a gravel guard 5012. As is shown in FIG. 27, the base 5004 is substantially "bowl" shaped having a first or vertically oriented wall 5016 (e.g., parallel to an axis 5024) along the perimeter thereof and a second or horizontally oriented wall 5020 (e.g., perpendicular to the axis 2024) at the downstream end thereof. Together, the first and second walls 2016, 5020 form a substantially "concave" shape. The second wall 5016 also includes an outlet cylinder 5028 extending axially from the second wall 5020 to produce an outlet 5032. The base 5004 also includes a flange 5036 extending radially outwardly from the first wall 5016 to produce an outer end 5040.

The base 5004 also includes a series of threaded apertures 5044 positioned at least partially within the "bowl" and spaced radially inwardly from the teeth 5048 of the gravel guard 5012.

The gravel guard 5012 of the roof drain 5000 rests against the flange portion 2036 of the base 5004 and includes a series of teeth 5048, and a plurality of bolt apertures 5052 spaced radially inwardly from the teeth 5048. The gravel guard 5012 also includes a plurality of gullets 5060 positioned between the teeth 5048 that are positioned vertically above the finished surface 5108 of the adjacent roof 5100 and vertically above the outer edge 5040 of the base 5004. The gullets 5060 are also positioned above the top surface 5064 of the gravel guard body 5068. When assembled, the gravel guard 5012 is secured to the base 5004 with fasteners 5072 extending through the bolt apertures 5052 and threaded into the threaded apertures 5044 of the base 5004.

As shown in FIG. 27, the dome 5008 of the drain 5000 is attached to the base 5004 via the gravel guard 5012 (e.g., it rests on the gravel guard 5012). The dome 5008 has a completely enclosed bottom edge 5076 and a completely enclosed transition area 5080.

FIGS. 1-5 illustrate a roof drain 10 configured to be installed on the roof 14 of a building. The roof drain 10 includes a base 18 at least partially defining a channel 38, a cage or dome 26, and a gravel guard or gravel ring 30. When installed, the channel 38 of the drain 10 is placed in fluid communication with a plumbing system 34 (e.g., a network of conduits to reroute the rainwater off of the roof) of the corresponding building such that water accumulating on the roof 14 is collected by the drain 10 and directed into the plumbing system 34 via the channel 38. More specifically, the roof drain 10 is configured to intake rain water and discharge the water into the plumbing system 34 producing a gravitational flow therein. Generally speaking, a gravitational flow system operates using the force of gravity to generate the flow therein typically through pitched piping and the like. Gravitational flow systems generally permit both air and water to enter the plumbing system 34. A gravitational system is different than a siphonic system which is configured to operate with the piping completely charged with water so that siphonic forces are utilized to encourage the flow of fluids therethrough.

The base 18 of the drain 10 is substantially “funnel” shaped defining the channel 38 through which rainwater may be directed into the plumbing system 34 of the building. More specifically, when rainwater collects on the roof 14, the water flows into the inlet 40 of the channel 38 where it is directed into the plumbing or drain system 34 via the outlet 22 thereof. In the illustrated embodiment, the base 18 includes a throat portion 42 at least partially defining the channel 38, and a flange portion 46 extending radially outwardly from the throat portion 42. Together, the throat portion 42 and flange portion 46 define a central axis 50. While the illustrated base 18 is cast as a single piece of material, it is to be understood that in alternative embodiments, the base 18 may be formed as multiple pieces coupled together.

The throat portion 42 of the base 18 is formed from a substantially annular wall 54 having an inner surface 58, a first end 62 generally corresponding with the inlet 40 of the channel 38, and a second end 66 opposite the first end 62 that generally corresponds with and forms the outlet 22 of the channel 38. The inner surface 58 is shaped such that the inner diameter 72 of the inner surface 58 continuously and smoothly decreases as it extends axially away from the first end 62 and toward the second end 66. More specifically, the cross-sectional shape of the inner surface 58, taken along the axis 50, forms a substantially convex shape over its entire axial length (see FIG. 7). The throat portion 42 also defines a frusto-conical-datum surface 76 generally defined as a

frusto-conically-shaped surface that is co-axial with the axis 50 and extends from the first end 62 to the second end 66. In such embodiments, the inner surface 58 is shaped such that it is always positioned radially inside the frusto-conical datum surface 76.

The inner surface 58 of the throat portion 42 forms a first surface angle 80a relative to the axis 50 at the first end 62 thereof and a second surface angle 80b relative to the axis 50 at the second end 66 thereof (see FIG. 4). In the illustrated embodiment, the first surface angle 80a is greater than the second surface angle 80b. Furthermore, the inner surface 58 smoothly transitions from the first surface angle 80a to the second surface angle 80b while always decreasing in value. In the illustrated embodiment, the first surface angle 80a is between approximately 40 and 70 degrees while the second surface angle 80b is between approximately 0 and 15 degrees. In other embodiments, the first angle 80a is between approximately 50 and 65 degrees. In still other embodiments, the first angle 80a is approximately one of 51 degrees, 52 degrees, 59 degrees, 60 degrees, and 62 degrees. Other embodiments, the second angle 80b may be between approximately 0 and 5 degrees. In still other embodiments, the second angle 80b may be approximately 3 degrees. In still other embodiments, the first angle 80a and second angle 80b may vary depending on the diameter of the outlet 22.

While the illustrated inner surface 58 provides a smooth, curved, convex shape, it is to be understood that alternative shapes may also be used. For example, FIG. 22 illustrates an alternative embodiment of the throat portion 42' having an alternative embodiment of the inner surface 58'. The inner surface 58' includes a frusto-conical portion 84' and a cylindrical portion 88' extending axially from the narrow end of the frusto-conical portion 84'. In such embodiments, the frusto-conical portion 84' includes a first constant surface angle 80a' that transitions to a second surface angle 80b' at the cylindrical portion 88'. Such an inner surface 58' does not include any concave portions (e.g., instances where the surface angle 80a', 80b' increases as it extends from the first end 62' to the second end 66').

The flange portion 46 of the base 18 extends radially outwardly from the first end 62 of the throat portion 42 to produce an outer edge 92. The outer edge 92, in turn, defines a top plane 96 (e.g., generally oriented normal to the axis 50 and positioned at the axial highest point of the base 18), and an outer diameter 100. The flange portion 46 includes a first portion 104 extending radially inwardly from the outer edge 92 at a first surface angle 108 relative to the axis 50, a second portion 112 extending radially inwardly from the first portion 104 at a second surface angle 116 relative to the axis 50, and a third portion 120 extending radially inwardly from the second portion 112 at a third surface angle 124. As shown in FIG. 8, the first surface angle 108 is less than the second surface angle 116 (e.g., the first surface angle 108 is steeper than the second surface angle 116), and the second surface angle 116 is less than the third surface angle 124 (e.g., the second surface angle 116 is steeper than the third surface angle 124).

When installed, the top plane 96 of the flange portion 46 is generally positioned so that is aligned with the top surface 130 of the roof 14 positioned immediately adjacent thereto. As such, any roof membrane or paper 152 can transition from the roof 14 to the base 18 without producing any high spots or bumps. For the purposes of this application, the top surface 130 of the roof 14 is generally defined as the surface upon which the roof paper 152 is laid (e.g., the top surface of the concrete) and does not include any gravel positioned thereon. Stated differently, the top surface 130 is substan-

tially aligned with the top plane 96. In alternative embodiments, the roof drain 10 may be mounted to a deck plate or other installation apparatus whereby the top surface 130 may include the upper surface of the deck plate upon which the roof paper 152 is laid proximate the roof drain 10.

When the drain 10 is assembled, the second portion 112 and second surface angle 116 are generally configured to match the angle and radial width of the underside of the gravel ring 30 (described below). Similarly, the third portion 120 and third surface angle 124 are generally set to match with the angle and radial size of the underside of the dome 26. (See FIG. 5). While the second and third portions 112, 120 are shown having different surface angles in the illustrated embodiment, it is understood that in other embodiments, they may be the same.

As shown in FIG. 5, the first portion 104 of the flange portion 46 is sized and shaped such that the outer edge 92 is positioned axially above the remainder of the flange portion 46 when the drain 10 is installed in an upright orientation (e.g., when the axis 50 is substantially vertical in orientation). With the drain 10 assembled, the first portion 104 is sized and shaped such that the outer edge 92 is positioned axially above the low point 126 of at least one gullet 128 of the gravel ring 30 (described below) and the base plates 132 of the dome 26 (described below). In the illustrated embodiment, the outer edge 92 is positioned axially above the low point 126 of each gullet 128 of the gravel ring 30 and above each base plate 132 of the dome 26. Stated differently, the low point 126 of at least one gullet 128 and at least one base plate 132 are positioned axially below the top plane 96. In the illustrated embodiment, the low point 126 of each gullet 128 and each base plate 132 are positioned axially below the top plane 96.

By elevating the outer edge 92 as described above, the drain 10 is configured so that water entering the drain 10 by flowing over the outer edge 92 (e.g., with the outer edge 92 installed level with the roof 14; see FIG. 4) will only encounter flow-paths that are vertically below the point of entry. As such, the water is able to more easily and efficiently flow into the channel 38. This is especially true when the water level on the roof 14 is low. Stated differently, the rainwater from the roof 14 can flow over the outer edge 92, through one or more guttels 128, over and between the dome base plates 132, and into the channel 38 without having to rise higher than the outer edge 92. Stated differently, the drain 10 is configured such that a continuous flow path can be traced from the outer edge 92 to the outlet 22 without rising above the top plane 96.

The base 18 also includes a first plurality of threaded apertures 136 formed into the flange portion 46 and outside the channel 38. During use, the threaded apertures 136 are configured to receive a threaded fastener 140 therein to couple the gravel ring 30 to the base 18. Similarly, the base 18 includes a second plurality of threaded apertures 144 on the underside thereof for securing the base 18 to the roof 14 or other building structure.

The base 18 also includes a cutting groove 148. The cutting groove 148 is formed into the base 18 at a first radial distance from the axis 50. During use, the cutting groove 148 is configured to receive and guide the tip of a knife or razor blade therein so the user can quickly and easily trim the roof paper 152 at the desired location. In the illustrated embodiment, the cutting groove 148 includes a "step" having two adjacent surfaces against which the user's blade may be pressed (e.g., into the corner formed by the two surfaces). However, in alternative embodiments, the groove 148 may be enclosed on three sides (not shown). In still other

embodiments, the cutting groove 148 may include other shapes and contours desirable to directing the user during the cutting process. While the illustrated groove 148 is annular in shape, in alternative embodiments, alternative shapes (e.g., polygonal, stepped, and the like) may also be present to produce the desired final cut dimensions. As shown in FIG. 6, the cutting groove 148 of the base 18 is positioned radially inward of the gravel ring 30. The cutting groove 148 is also positioned radially inwardly of the outer diameter 156 of the dome 26 (described below). In some embodiments, the cutting groove 148 may be positioned at a location where the throat portion 42 meets the flange portion 46 at the radially inner barrier of the third portion 120 of the flange portion 46.

As shown in FIG. 4, the outlet 22 of the channel 38 generally defines an outlet diameter 24 generally corresponding to the size of the pipes forming the downspout of the plumbing system. For example, an outlet 22 having a 2" diameter substantially corresponds with a downspout formed from 2" pipe, an outlet having a 3" diameter substantially corresponds with a downspout formed from 3" pipe, and the like. It is understood that the size of the drain 10 may vary proportionally dependent upon the outlet diameter 24 of the outlet 22.

Illustrated in FIGS. 9-11, the dome 26 of the roof drain 10 is coupleable to the flange portion 46 of the base 10 and configured to at least partially enclose the inlet 40 of the channel 38. More specifically, the dome 26 acts as a filter by not allowing large items (e.g., rocks, sticks, and other debris) to enter the channel 38 during use. The dome 26 is also configured to maximize the volume of water that may flow into the channel 38 at any given time. The dome 26 does this by maximizing the percentage of the exterior surface area thereof that is open for water to pass therethrough for a given dome 26 size.

The dome 26 is substantially cylindrical in shape having an upper surface 160 and a side surface 164 extending along the perimeter for the upper surface 160. The dome 26 also includes a core element 168 defining a central axis 172, a plurality ribs 176 extending radially outwardly from the core element 168, and a plurality of crossbars 180 extending between and interconnecting select adjacent ribs 176. The core element 168 of the dome 26 is substantially disk shaped having a central disk 184 defining a plurality of apertures 188 therein, a concentric ring 192 spaced radially outward from the central disk 184, and a plurality of splines 196 extending radially between the central disk 184 and the concentric ring 192. The core element 168 also defines an outer core diameter 200. In alternative embodiments, additional styles and shapes of core elements may be present such as, but not limited to, a solid or perforated disk, a dish-shaped element, a plurality of concentrically located rings, a plurality of radially or otherwise oriented splines, and the like.

The ribs 176 of the dome 26 each extend radially outwardly from the core element 168 to produce a respective distal end 204. Together, the ribs 176 are generally spaced equally from one another in a circumferential direction to produce a plurality of equally sized gaps 208 therebetween. Each rib 176, in turn, includes a first leg or portion 212 extending radially outwardly from the core element 168, and a second leg or portion 216 extending from the first leg 212 at an angle with respect thereto to produce the distal end 204. Each rib 176 also includes a bend or transition 220 where the first leg 212 and second leg 216 meet.

As shown in FIG. 9, the first leg 212 of each rib 176 is oriented substantially perpendicular to the axis 172 (e.g.,

forming an angle therebetween of approximately 70 and 100 degrees, for example 81 degrees) and generally corresponds with the upper surface 160 while the second leg 216 of each rib 176 is oriented substantially parallel to the axis 172 (e.g., forming an angle therebetween of approximately 0 and 20 degrees, for example 12 degrees) and generally corresponds with the side surface 165 of the dome 26. In still other embodiments, the first leg 212 and the second leg 216 form an angle therebetween of approximately 90 to 120 degrees, for example 112 degrees.

The crossbars 180 of the dome 26 extend between and are coupled to adjacent ribs 176. Each crossbar 180 is generally positioned at various locations along the lengths of the ribs 176 and oriented substantially perpendicular thereto. As shown in FIG. 9, the crossbars 180 are positioned such that no crossbars 180 are located at the transition 220 between the first leg 212 and the second leg 216 (e.g., the transition 220 region of the dome 26 is not completely enclosed). Stated differently, each gap 208 of the dome 26 is open at the transition 220. The crossbars 180 are also positioned such that each crossbar 180 is not aligned with any crossbars 180 positioned in the adjacent gaps 208. While the illustrated crossbars 180 are generally elongated in shape and oriented perpendicular to the corresponding ribs 176, it is understood that in alternative embodiments the crossbars 180 may have different sizes and shapes and be oriented at various angles relative to the ribs 176.

In the illustrated embodiment, the dome 26 includes a first set of crossbars 1180 and a second set of crossbars 2180. Each crossbar 1180 of the first set of crossbars extends between the first legs 212 of the ribs 176 and are each located at a first radial distance 224 from the axis 172. As shown in FIG. 10, the first set of crossbars 1180 are located in every-other gap 208 around the circumference of the dome 26. In the illustrated embodiment, the first radial distance 224 is greater than the outer core diameter 200 but less than the diameter at which the transition 220 is located. In alternative embodiments, the first set of crossbars 1180 may be positioned in different patterns such as, but not limited to, having each crossbar 1180 at a different radial distance than adjacent crossbars; having the crossbars spiral radially outwardly or inwardly, having a random pattern where no adjacent crossbars align, and the like.

Each crossbar 2180 of the second set of crossbars extends between the second legs 216 of the ribs 176 at a corresponding “bar height” 228. For the purposes of this application, the bar height 228 is generally defined as the distance between the crossbar 180 and the distal end 204 of the corresponding rib 176.

The second set of crossbars 2180 are generally positioned so that they alternate above and below a datum plane 232 oriented normal to the axis 172 and located at a predetermined datum height 236. For the purposes of this application, the datum height 236 is generally defined as the axial distance between the datum plane 232 and the base plane 240 of the dome 26 (described below). In some embodiments, the datum plane 232 may be positioned at the midpoint such that the datum height 236 is half the overall axial height 244 of the dome 26. In other embodiments, the datum plane 232 may be positioned at different datum heights 236 to accommodate different flow patterns.

As shown in FIG. 11, the second set of crossbars 2180 are positioned such for a given crossbar 2180, both adjacent crossbars 2180b are located to one side thereof (e.g., either above or below). For example, for a select crossbar 2180 having a given bar height 228, both adjacent crossbars 2180

will have a bar height 228 that is either both greater than or both less than the given bar height 228.

More specifically, the second set of crossbars 2180 are positioned to produce a repeating pattern about the circumference of the dome 26. Specifically, the first crossbar 2180a of the pattern includes a first bar height 228a, the subsequent second crossbar 2180b has a second bar height 228b that is greater than the first bar height 228a, the subsequent third crossbar 2180c has a third bar height 228c that is less than the second bar height 228b, the subsequent fourth crossbar 2180d has a fourth bar height 228d that is greater than the third bar height 228c, the subsequent fifth crossbar 2180e has a fifth bar height 228e that is less than the fourth bar height 228d, and the subsequent sixth crossbar 2180f has a sixth bar height 228f that is greater than the fifth bar height 228e. In instances where six crossbars 2180 are included in the pattern, the sixth bar height 228f is also greater than the first bar height 228a. However, in alternative embodiments, additional or fewer crossbars 2180 may be included in the pattern as necessary (e.g., four crossbars, five crossbars, seven crossbars, eight crossbars, nine crossbars, and the like).

As shown in FIG. 11, in addition to the alternating pattern of the crossbars 2180 described above, the second set of crossbars 2180 also step-down (e.g., the bar heights 228 reduce) as the pattern progresses. For example, for the sub-set of crossbars 2180 positioned above the datum plane 232 (e.g., the second, fourth, and sixth crossbars 2180b, 2180d, 2180f, the fourth bar height 228d is less than second bar height 228b and the sixth bar height 228f is less than the fourth bar height 228d. With respect to the sub-set of crossbars 2180 positioned below the datum plane 232 (e.g., the first, third, and fifth crossbars 2180a, 2180c, 2180e), the third bar height 228c is less than the first bar height 228a and the fifth bar height 228e is less than the third bar height 228c. Viewed together as a group, none of the six crossbars 2180 in the repeating pattern have the same bar height 228 (e.g., the first, second, third, fourth, fifth, and sixth bar heights 228a-f are all different).

FIG. 23 illustrates another embodiment of the second set of crossbars 2180'. The second set of crossbars 2180' produce a “step-down” pattern where each crossbar 2180' has a bar height 228 that is less than the previous crossbar 2180' when taken in a given rotational direction. In such embodiments, the illustrated pattern may repeat over the circumference of a given dome. While the illustrated pattern shows six crossbars 2180', it is understood that more or fewer crossbars 2180' may be present.

FIG. 24 illustrates another embodiment of the second set of crossbars 2180''. The second set of crossbars 2180'' generally produces an alternating pattern where groups of crossbars 2180'' (e.g., two crossbars) alternate above and below the datum 232. While the illustrated embodiment includes two crossbars 2180'' in each group, alternative embodiments may include more or fewer crossbars 2180'' in each group. Furthermore, while the illustrated embodiment shows the crossbars 2180'' in a given group not aligning with each other, it is understood that in some embodiments the crossbars 2180'' within a given group may align with each other.

FIG. 25 illustrates another embodiment of the second set of crossbars 2180'''. The second set of crossbars 2180''' generally produces a “step-up” pattern where each crossbar 2180''' has a bar height 228 that is greater than the previous crossbar 2180''' when taken in a given rotational direction. In such embodiments, the illustrated pattern may repeat over the circumference of a given dome. While the illustrated

pattern shows six crossbars 2180", it is understood that more or fewer crossbars 2180" may be present.

FIG. 26 illustrates another embodiment of the second set of crossbars 2180"". The second set of crossbars 2180"" generally produces a "chevron" pattern where the crossbars 2180"" alternate between step-up and step-down patterns. In the illustrated embodiment, the alternating step-up and step-down patterns continue over the entire circumference of the dome.

While the illustrated crossbars 180 are oriented as described above, it is understood that additional patterns may be present. Furthermore, the pattern may be expanded to include more or fewer crossbars 180 as necessary and to accommodate different numbers of ribs 176 and dome 26 sizes.

The dome 26 also includes a set of base plates 132, each coupled to the distal end 204 of one or more ribs 176 and configured to support the dome 26 on the base 18. In the illustrated embodiment, the base plates 132 do not completely enclose the bottom of the dome 26, rather, at least one of the gaps 208 between adjacent ribs 176 are open (e.g., not enclosed at the bottom of the dome 26). When the drain 10 is assembled, the base plates 132 are positioned completely axially below the top plane 96. Furthermore, the gaps between the base plate 132 also extend axially below the top plane 96. As shown in FIG. 4, the base plates 132 are also positioned below the finished surface 146 of the roof 14 positioned immediately adjacent to the drain 10. For the purposes of this application, the finished surface 146 of the roof 14 is defined as the surface of the roof on which gravel is laid immediately adjacent to the drain 10. In FIG. 4, the finished surface 146 is the top surface of the roof paper 152, however, the finished surface 146 may include the top surface 130 of the roof 14 (e.g., when no paper 152 is present) or the top surface of a deck plate immediately adjacent to the drain 10 (not shown) when used. The gaps between the base plates 132 also extend below the finished surface 146 of the roof 14 positioned immediately adjacent to the drain 10.

As shown in FIG. 9, the base plates 132 of the dome 26 include a first set of locating base plates 1132 and a second set of intermediate base plate 2132. Together, the first set and second set of plates 1132, 2132 define a base plane 240 of the dome 26. As shown in FIG. 11, the base plane 240 is generally oriented substantially normal to the axis 172. In the illustrated embodiment, the bottom surfaces 252 of the base plates 132 are all slightly angled relative to the axis 172 so that bottom surfaces 252 substantially match and align with the flange portion 46 of the base 18 (e.g., the third portion 120). However, in alternative embodiments it is understood that the bottom surfaces 252 may be normal to the axis 172 or contoured as necessary to accommodate the base 18 and the gravel ring 30. In some embodiments, protrusions or grooves may be included to aid the alignment between the dome 26, gravel ring 30, and base 18. Together, the base plates 132 also define an outer diameter 156 of the dome.

The first set of base plates 1132 are each substantially elongated in shape extending along and being coupled to one or more distal ends 204 of the ribs 176. During use, the first set of base plate 1132 generally form locking members 256 and are configured to interact with and releasably couple to the gravel ring 30. In the illustrated embodiment, the dome 26 includes three first base plates 1132, each positioned so that they generally correspond and align with a respective locking member 260 of the gravel ring 30 (described below).

The locking members 256 of the dome 26 are configured to both restrict the axial movement of the dome 26 relative to the base 18 (e.g., clamp the dome 26 to the base 18) and rotationally orient the dome 26 relative to both the base 18 and gravel ring 30. As shown in FIG. 9, the illustrated locking members 256 each include a locking ridge 264 and define a locking notch 266 open to the radially outermost edge thereof.

The second set of base plates 2132 are each configured to strengthen and enclose adjacent ribs 176 of the dome 26. As shown in FIG. 9, each base plate 2132 of the second set of base plates extends between and is coupled to the distal ends 204 of adjacent ribs 176. Together, the base plates 2132 are generally spaced apart so that they form alternating open and closed gaps 208 between the ribs 176. While the illustrated plates 2132 are shown to be positioned in every other gap 208, it is understood that in alternative embodiments the size (e.g., the number of ribs 176 an individual base plate 2132 is coupled to) and spacing (e.g., the number of open gaps 208 between adjacent base plates 2132) may be adjusted as needed.

FIGS. 12-14 illustrate the gravel ring 30 of the roof drain 10. The gravel ring 30 is generally configured to releasably couple the dome 26 to the base 18 in addition to acting as a preliminary filter by restricting the flow of large debris (e.g., gravel, sticks, garbage, and the like) from flowing into the dome 26 and/or channel 38. During installation, the gravel ring 30 is also configured to secure the roof paper 152 to the base 18 of the drain 10.

As shown in FIG. 12, the gravel ring 30 is substantially disk shaped having an annular body 270 defining an outer diameter 274 and an axis 278 therethrough. The gravel ring 30 also includes a plurality of locking members 260, and a plurality of teeth 286.

The body 270 of the gravel ring 30 is annular in shape and defines an outer diameter 290, an inner diameter 294, and an upper surface 296. As shown in FIG. 13, the inner diameter 294 of the body 270 includes a plurality of notches 300 formed therein. Each notch 300 extends radially outwardly (e.g., into the body 270) and is equally spaced along the circumference of the inner diameter 294. During use, the notches 300 allow the user to more easily identify the roof paper 152 when installing the drain 10 onto a roof 14. More specifically, by having the notches 300 formed therein, the user is not required to have as much sheeting inside the drain 10 to satisfy the "visible length" code requirements. Since the presence of roof paper 152 near the channel 38 can disrupt flow patterns and reduce overall flow capacity, minimizing the amount of paper 152 can improve flow characteristics of the drain 10. While the illustrated notches 300 are sized and shape equally about the circumference of the body 270, in alternative embodiments, more or fewer notches 300 may be present. Furthermore, the size and the shape of the notches 300 may vary with respect to one another.

The locking members 260 of the gravel ring 30 are configured to releasably engage with the locking members 256 of the dome 26. More specifically, the locking members 260 of the gravel ring 30 are configured to axially lock the dome 26 against the base 18 while also rotationally aligning the ring 30, dome 26, and base 18. In the illustrated embodiment, the locking members 260 of the gravel ring 30 include a plurality of tabs extending radially inwardly from the body 270 to produce a distal end 304 at a distal end diameter 308. As shown in FIG. 3, the distal end diameter 308 is less than the outer diameter 154 of the dome 26.

11

The teeth 286 of the gravel ring 30 extend axially from upper surface 296 of the body 270 and are spaced in equal groups about the circumference thereof. More specifically, the illustrated teeth 286 include six groups of six equally spaced teeth 286, each separated by a corresponding bolt aperture 312. Together, the teeth 286 and bolt apertures 312 are all equally spaced about the circumference of the gravel ring 30 and generally located at the same radial distance from the axis 278 (e.g., on the same reference circle centered on the axis 278). As such, when the gravel ring 30 is installed, the head 314 of the fasteners 318 positioned in the bolt apertures 312 serve to act as a "tooth" in the gravel ring 30. By doing so, the fasteners 318 are both easily accessible by the user while minimizing any restrictions to the water flow past the ring 30 itself. As shown in FIG. 4, bolt apertures 312 are positioned radially outside the dome 26.

As shown in FIG. 14, each tooth 286 is substantially "diamond" shaped having a leading point 316 positioned proximate the outer diameter 290 of the body 270, and a trailing point 320 positioned proximate the inner diameter 294 of the body 270. As shown in FIG. 14, the leading point 316 and trailing point 320 of each tooth 286 falls on a datum line 324 extending radially from the axis 278.

Each tooth 286 also includes a leading angle 328 and a trailing angle 332. For the purposes of this application, the leading angle 328 is generally defined as the angle at which the tooth 286 extends from the leading point 316 while the trailing angle 332 is generally defined as the angle at which the tooth 286 extends from the trailing point 320. As shown in FIG. 14, the leading angle 328 is greater than the trailing angle 332. Each tooth 286 is also shaped so that it tapers as it extends axially from the upper surface 296 body 270.

The gravel ring 30 also includes a plurality of guttels 128 formed between a corresponding pair of teeth 286, between a tooth 286 and bolt aperture 312 (e.g., the head 314 of the fastener 318 positioned in the bolt aperture 312), or between a tooth 286 and a locking member 260. The guttels 128, are equally spaced about the entire circumference of the gravel ring 30, including those guttels 128 associated with the bolt apertures 312 and locking members 260.

Each gullet 128, in turn, includes a low point or bottom 336. In the illustrated embodiment, the low point 336 of the guttels 128 lie directly on the upper surface 296 of the body 270. As shown in FIG. 5, the guttels 128 are configured such that, when the gravel ring 30 is attached to the base 18, the low point 336 of at least one gullet 128 is positioned axially beneath the top plane 96. In the illustrated embodiment, each low point 336 is positioned below the top plane 96. Furthermore, the low point 336 of at least one gullet 128 is positioned below the finished surface 146 of the roof 14 immediately adjacent to the drain 10.

In the illustrated embodiment, the number of guttels 128 on the gravel ring 30 and the number of gaps 208 in the dome 26 are multiples of one another. As such, when both the gravel ring 30 and dome 26 are attached to the base 18 (and rotationally aligned using the locking members 256, 260), each of the guttels 128 may be radially aligned with a corresponding gap 208 (e.g., when the number of guttels 128 is less than or equal to the number of gaps 208) or each gap 208 may be radially aligned with a corresponding gullet 128 (e.g., when the number of gaps 208 is less than or equal to the number of guttels 128). This arrangement allows for a more efficient and direct flow path for water to enter the channel 38 during use. In the illustrated embodiment, the number of guttels 128 equals the number of gaps 208.

12

While the illustrated drain 10 is shown being substantially circular in shape, it is understood that in alternative embodiments, the drain 10 may be rectangular, square, oval, or polygonal in shape.

5 To install the drain 10 on a roof 14, the user places the base 18 such that the outer edge 92 of base 18 is located substantially level with the top surface 130 of the roof 14 (e.g., the top plane 96 is aligned with the top surface 130; see FIG. 4). With the base 18 located, the user may then secure 10 the drain 10 in place by bolting the base 18 to the roof 14 with fasteners (e.g., using threaded apertures 144 on the bottom side thereof). The user may also attach the outlet 22 of the drain 10 to the building plumbing system 34.

With the base 18 in place, the user may then apply a layer 15 of roof paper 152 to the top surface 130 of the roof 14. When doing so, the user lays the paper 152 over the outer edge 92 so it generally covers the base 18. With the paper 152 roughly positioned, the user may then attach the gravel ring 30 to the base 18. To do so, the user axially places the gravel ring 30 onto the flange portion 46, making sure to align the bolt apertures 312 of the ring 30 with the corresponding threaded apertures 136 of the base 18. The user may then secure the ring 30 to the base 18 using a series of threaded fasteners 318 (see FIG. 1).

25 With the ring 30 in place, the user may then trim the roof paper 152 by running a blade (e.g., a razor blade or knife) along the cutting groove 148 of the base 18. By doing so, the cutting groove 148 will guide the blade along the desired cutting path, allowing the user to remove the portion of the 30 paper 152 generally covering the channel 38. As described above, the cutting groove 148 is positioned such that the appropriate length and shape of paper 152 remains attached to the drain 10 as required by code. Furthermore, the notches 300 of the gravel ring 30 are positioned such that an 35 increased length of roof paper 152 is exposed after the excess paper has been removed (e.g., the exposed radial length of paper 152 equals the radius of the interior of the notch 300 minus the radius at which the cutting groove 148 is located).

40 Finally, the user may install the dome 26. To do so, the user aligns each locking member 260 of the gravel ring 30 with a corresponding locking member 256 of the dome 26. More specifically, the user aligns the elements to that the of the gravel ring 30 with a corresponding locking notch 266 of 45 the dome 26. The dome 26 is then axially directed onto the base 18 until the bottom surfaces 252 of the dome 26 contacts the flange portion 46 of the base 18. By doing so, each locking member 260 passes through their corresponding notch 266.

Once in place, the user can then rotate the dome 26 relative to the base 18 and gravel ring 30 causing each locking member 260 to pass over the top of its corresponding base plate 132 until each locking member 260 contacts a respective locking ridge 264. With the locking member 55 260 in contact with the ridge 264, the dome 26 and ring 30 are rotationally aligned such that the guttels 128 of the ring 30 radially align with the gaps 208 of the dome 26.

FIGS. 15-17 illustrate another embodiment of the gravel ring 30'. The gravel ring 30' is substantially similar to the 60 gravel ring 30 so only the difference will be discussed in detail herein. The gravel ring 30' includes a plurality of teeth 286', and one or more bolt apertures 312'. Together, the teeth 286' and bolt apertures 312' are equally spaced along the circumference of the body 270' of the ring 30' with a gullet 65 128' being formed between each element. As shown in FIG. 16, both the teeth 286' and bolt apertures 312' are all located substantially the same radial distance from the axis 278'.

13

The gravel ring 30' includes a plurality of teeth 286' having a substantially chevron shape. More specifically, each tooth 286' includes a leading surface 1000' positioned proximate to and facing the outer diameter 290' of the ring 30' body 270', and a trailing surface 1004' opposite the leading surface 1000' and facing the inner diameter 294' of the body 270'. Each tooth also narrows as it extends axially from the body 270'.

The leading surface 316' is substantially convex, extending outwardly away from the tooth 286. In the illustrated embodiment the leading surface 316' includes a pair of planar surfaces set at an angle relative to one another to form a point 1008' and facing radially outwardly. More specifically, the planar surfaces are oriented such that they extend away from each other as they extend radially inwardly. In alternative embodiments, the leading surface 316' may include a single, convex curved surface as well.

The trailing surface 1004' is substantially concave, extending inwardly into the tooth 286. In the illustrated embodiment, the trailing surface 1004' includes a curved concave surface. However, in alternative embodiments multiple planar surfaces may also be used.

The gullets 128' of the ring 30' each include a low point or bottom 336" that, when installed on a base 18, is below the top plane 96. In the illustrated embodiment, the bottom 336" of the gullet 128' is coincident with the top surface 296' of the body 270'. Furthermore, the illustrated ring 30' includes the same number of gullets 128' as the number of gaps 208 in the dome 26. In alternative embodiments, the ring 30' may include a number of gullets 128' that is a multiple of the number of gaps 208 in the dome 26.

FIGS. 18-20 illustrate another embodiment of the gravel ring 30". The gravel ring 30" is substantially similar to the gravel ring 30 so only the differences will be discussed in detail herein. The gravel ring 30" includes a plurality of teeth 286", and one or more bolt apertures 312". Together, the teeth 286" and bolt apertures 312" are equally spaced along the circumference of the body 270" of the ring 30" with a gullet 128" being formed between each item. As shown in FIG. 19, both the teeth 286" and bolt apertures 312" are all located substantially the same radial distance from the axis 278".

The gullets 128" of the ring 30" each include a low point or bottom 336" that, when installed on a base 18, is below the top plane 96. In the illustrated embodiment, the bottom 336" of the gullet 128" is coincident with the top surface 296" of the body 270". Furthermore, the illustrated ring 30" includes the same number of gullets 128" as the number of gaps 208 in the dome 26. In alternative embodiments, the ring 30" may include a number of gullets 128" that is a multiple of the number of gaps 208.

The teeth 286" of the ring 30" are substantially rectangular in shape having a wider circumferential dimension than radial dimension. Each tooth 286" also narrows as it extends axially from the top surface 296" of the body 270". While the illustrated teeth 286" are rectangular, in alternative embodiments, different shapes may be used. In still other embodiments, the size and shape of the teeth 286" may vary on a single ring 30" (e.g., a portion of the teeth 286" are rectangular, a portion are diamond, and the like).

FIG. 21 illustrates another embodiment of the dome 26". The dome 26" is substantially similar to the dome 26 so only the differences will be discussed herein. The core element 168" of the dome 26" includes a plurality of concentric rings 2000" interconnected by a plurality of radially expending splines 2004" to produce an outer core diameter 200". The dome 26" also includes a plurality of ribs 176"

14

extending radially outwardly from the core element 168" to produce a corresponding distal end 204". The dome 26" does not include any crossbeams outside the core element 168". Furthermore, the dome 26" does not include any crossbeams proximate the transition 220" of each rib 176". Stated differently, the gaps 208" between each rib 176" is not covered proximate the transition 220".

FIGS. 28-30 illustrate the flow characteristics of some embodiments of the drain 10 (identified as line "A") as compared to a traditional roof drain (identified as line "B"). In some embodiments, the drain 10 is configured to flow between 75 and 150 GPM at 1" of head pressure. For the purposes of this application, the head pressure is measured as the depth of the water above the top plane 96 of the drain 10. In other embodiments, the drain 10 is configured to flow between 90 and 110 GPM at 1" of head pressure. In still other embodiments, the drain 10 is configured to flow between 75 and 100 GPM at 1" of head pressure. In still other embodiments, the drain 10 is configured to flow approximately 100 GPM at 1" of head pressure. In still other embodiments, the drain 10 is configured to flow at least 75 GPM at 1" of head pressure. In still other embodiments, the drain 10 is configured to flow at least 100 GPM at 1" of head pressure.

In still other embodiments, the drain 10 is configured to flow between 40 and 120 GPM at 1" of head pressure with an output diameter 24 of 2". In another embodiment, the drain 10 is configured to flow between 80 and 180 GPM at 1" of head pressure with an output diameter 24 of 2". In still other embodiments, the drain 10 is configured to flow between 90 and 110 GPM at 1" of head pressure with an output diameter 24 of 2". In still other embodiments, the drain 10 is configured to flow approximately 100 GPM at 1" of head with an output diameter 24 of 2".

In still other embodiments, the drain is configured to flow between 225 and 400 GPM at 2" of head pressure with an outlet diameter 24 of 4". In still other embodiments, the drain 10 is configured to flow between 225 and 375 GPM at 2" of head pressure with an outlet diameter 24 of 4". In still other embodiments, the drain 10 is configured to flow between 300 and 400 GPM at 2" of head pressure with an outlet diameter 24 of 4". In still other embodiments, the drain 10 is configured to flow between 350 and 400 GPM at 2" of head with an outlet diameter 24 of 4". In still other embodiments, the drain 10 is configured to flow approximately 350 GPM at 2" of head with an outlet diameter 24 of 4". In still other embodiments, the drain 10 is configured to flow greater than 225 GPM at 2" of head pressure with an outlet of 4". In still other embodiments, the drain 10 is configured to flow at least 250 GPM at 2" of head pressure with an outlet diameter of 4". In still another embodiment, the drain 10 is configured to flow at least 250 GPM at 2" of head with an outlet of at least 3".

In still other embodiments, the drain 10 is configured to flow between 200 and 350 GPM at 2" of head pressure with an outlet diameter 24 of 3". In still other embodiments, the drain 10 is configured to flow between 200 and 325 GPM at 2" of head pressure with an outlet diameter 24 of 3". In still other embodiments, the drain 10 is configured to flow between 300 and 400 GPM at 2" of head pressure with an outlet diameter 24 of 3". In still other embodiments, the drain 10 is configured to flow between 300 and 350 GPM at 2" of head pressure with an outlet diameter 24 of 3". In still other embodiments, the drain 10 is configured to flow approximately 325 GPM at 2" of head pressure with an outlet diameter of 3". In still other embodiments, the drain 10 is configured to flow greater than or equal to 325 GPM

at 2" of head pressure with an outlet diameter of 3". In still other embodiments, the drain **10** is configured to flow at least 200 GPM at 2" of head pressure with an outlet diameter of 3".

In still other embodiments, the drain **10** is configured to reach 90% maximum flow rate at less than 2" of head pressure. For the purposes of this application, the maximum flow rate of the drain **10** is generally defined as the maximum rate of flow that can pass through the drain **10** having a downpipe with a diameter equal to the outlet diameter **24** of the outlet **22** attached thereto.

In still other embodiments, the drain **10** is configured to reach 90% maximum flow rate at less than 2" of head pressure with an outlet diameter of 2". In still other embodiments, the drain **10** is configured to reach 90% maximum flow rate at between 1" and 2" of head pressure with an outlet diameter of 2". In still other embodiments, the drain **10** is configured to reach 90% maximum flow rate at 1.5" of head pressure or less with an outlet diameter **24** of 2". In still other embodiments, the roof drain is configured to reach 90% maximum flow rate at less than 2" of head pressure with an outlet diameter of 2".

In still other embodiments, the drain **10** is configured to reach 90% maximum flow rate at less than 5" of head pressure with an outlet diameter **24** of 4". In still other embodiments, the drain **10** is configured to reach 90% maximum flow rate at between 3" and 4" of head pressure with an outlet diameter **24** of 4". In still other embodiments, the drain **10** is configured to reach 90% maximum flow rate at between 3.5" and 4" of head pressure with an outlet diameter **24** of 4". In still other embodiments, the drain **10** is configured to reach 90% maximum flow rate at approximately 3.5" of head pressure with an outlet diameter **24** of 4". In still other embodiments, the drain **10** is configured to reach 90% maximum flow rate at less than 4" of head pressure with an outlet diameter **24** of 4". In still other embodiments, the drain **10** is configured to reach 90% maximum flow rate at less than 4.5" of head pressure with an outlet diameter of 4".

In still other embodiments, the drain **10** is configured to reach 90% maximum flow rate at less than 4" of head pressure with an outlet diameter **24** of 3". In still other embodiments, the drain **10** is configured to reach 90% maximum flow rate at less than 3" of head pressure with an outlet diameter **24** of 3". In still other embodiments, the drain **10** is configured to reach 90% maximum flow rate at between 2" and 3" of head pressure with an outlet diameter **24** of 3". In still other embodiments, the drain **10** is configured to reach 90% maximum flow rate at between 2.5" and 3" of head pressure with an outlet diameter **24** of 3". In still other embodiments, the drain **10** is configured to reach 90% maximum flow rate at approximately 2.5" of head pressure with an outlet diameter **24** of 3". In still other embodiments, the drain **10** is configured to reach 90% maximum flow rate at less than 3.5" of head pressure with an outlet diameter of 3".

In some embodiments, the flow rates set forth above may be determined by attaching a 10 foot long vertically oriented downpipe to the outlet **22** of the drain **10** and then running a test measuring the flow rate through the drain **10** and downpipe. In such embodiments, the 10 foot long vertically oriented downpipe would have a size substantially corresponding to the outlet diameter **24** of the drain **10**. Furthermore, in some embodiments the roof drain may be installed in a test stand according industry standard ASME A112.6.4. Similarly, a test protocol to gather the data may also be conducted in accordance with ASME A112.6.4.

FIGS. 35 and 36 illustrate the flow characteristics of the drain **10** when tested having a 4 foot long vertically oriented drain pipe with the indicated output diameter attached thereto. The tests were conducted in accordance with standard ASME A112.6.4 as it pertains to gravity roof drains. The drain **10** is configured so that it will not transition from gravity flow characteristics to siphonic flow characteristics, under testing conditions, for at least 5 minutes. All head pressures are measured relative to the top plane **96**.

10 In some embodiments, the drain **10** is configured to flow between 80 GPM and 125 GPM at 1 inch of head pressure. In still other embodiments, the drain **10** is configured to flow between 150 GPM and 445 GPM at 2 inches of head pressure. In still other embodiments, the drain **10** is configured to flow between 300 GPM and 350 GPM at 2 inches of head pressure. In still other embodiments, the drain **10** is configured to flow between 310 GPM and 330 GPM at 2 inches of head pressure.

15 In some embodiments, the drain **10** is configured to flow between 80 and 90 GPM at 1 inch of head pressure with an outlet diameter **24** of 2". In still other embodiments, the drain **10** is configured to flow approximately 85 GPM at 1 inch of head pressure with an outlet diameter **24** of 2". In still other embodiments, the drain **10** is configured to flow between 140 and 150 GPM with an outlet diameter **24** of 2". In still other embodiments, the drain **10** is configured to achieve 90% maximum flow at less than 1.5 inches of head pressure and an outlet diameter **24** of 2".

20 In some embodiments, the drain **10** is configured to flow between 80 and 90 GPM at 1 inch of head pressure with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4". In still other embodiments, the drain **10** is configured to achieve 90% maximum flow at less than 1.5 inches of head pressure and an outlet diameter **24** of 4".

25 In some embodiments, the drain **10** is configured to flow between 80 and 90 GPM at 1 inch of head pressure with an outlet diameter **24** of 3". In still other embodiments, the drain **10** is configured to flow approximately 85 GPM at 1 inch of head pressure with an outlet diameter **24** of 3". In still other embodiments, the drain **10** is configured to flow between 140 and 150 GPM with an outlet diameter **24** of 3". In still other embodiments, the drain **10** is configured to achieve 90% maximum flow at less than 1.5 inches of head pressure and an outlet diameter **24** of 3".

30 In some embodiments, the drain **10** is configured to flow between 80 and 90 GPM at 1 inch of head pressure with an outlet diameter **24** of 3". In still other embodiments, the drain **10** is configured to flow approximately 85 GPM at 1 inch of head pressure with an outlet diameter **24** of 3". In still other embodiments, the drain **10** is configured to flow between 140 and 150 GPM with an outlet diameter **24** of 3". In still other embodiments, the drain **10** is configured to achieve 90% maximum flow at less than 1.5 inches of head pressure and an outlet diameter **24** of 3".

35 In some embodiments, the drain **10** is configured to flow between 80 and 150 GPM at 1 inch of head pressure with an outlet diameter **24** of 3". In still other embodiments, the drain **10** is configured to flow approximately 85 GPM at 1 inch of head pressure with an outlet diameter **24** of 3". In still other embodiments, the drain **10** is configured to flow between 140 and 150 GPM with an outlet diameter **24** of 3". In still other embodiments, the drain **10** is configured to achieve 90% maximum flow at less than 1.5 inches of head pressure and an outlet diameter **24** of 3".

40 In some embodiments, the drain **10** is configured to flow between 80 and 150 GPM at 1 inch of head pressure with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4". In still other embodiments, the drain **10** is configured to achieve 90% maximum flow at less than 1.5 inches of head pressure and an outlet diameter **24** of 4".

45 In some embodiments, the drain **10** is configured to flow between 80 and 150 GPM at 1 inch of head pressure with an outlet diameter **24** of 3". In still other embodiments, the drain **10** is configured to flow approximately 85 GPM at 1 inch of head pressure with an outlet diameter **24** of 3". In still other embodiments, the drain **10** is configured to flow between 140 and 150 GPM with an outlet diameter **24** of 3". In still other embodiments, the drain **10** is configured to achieve 90% maximum flow at less than 1.5 inches of head pressure and an outlet diameter **24** of 3".

50 In some embodiments, the drain **10** is configured to flow between 80 and 150 GPM at 1 inch of head pressure with an outlet diameter **24** of 3". In still other embodiments, the drain **10** is configured to flow approximately 85 GPM at 1 inch of head pressure with an outlet diameter **24** of 3". In still other embodiments, the drain **10** is configured to flow between 140 and 150 GPM with an outlet diameter **24** of 3". In still other embodiments, the drain **10** is configured to achieve 90% maximum flow at less than 1.5 inches of head pressure and an outlet diameter **24** of 3".

55 In some embodiments, the drain **10** is configured to flow between 80 and 100 GPM at 1 inch of head pressure with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4". In still other embodiments, the drain **10** is configured to flow approximately 85 GPM at 1 inch of head pressure with an outlet diameter **24** of 4". In still other embodiments, the drain **10** is configured to flow between 140 and 150 GPM with an outlet diameter **24** of 4".

with an outlet diameter **24** of 4". In still other embodiments, the drain **10** is configured to flow between 620 and 350 GPM with an outlet diameter **24** of 4". In still other embodiments, the drain **10** is configured to flow approximately 630 GPM with an outlet diameter **24** of 4". In still other embodiments, the drain **10** is configured to achieve 90% maximum flow at 3 inches or less of head pressure and an outlet diameter **24** of 4".

In some embodiments, the drain **10** is configured to flow between 100 and 130 GPM at 1 inch of head pressure with an outlet diameter **24** of 6". In still other embodiments, the drain **10** is configured to flow approximately 102 GPM at 1 inch of head pressure with an outlet diameter **24** of 6". In still other embodiments, the drain **10** is configured to flow between 350 and 700 GPM at 2 inches of head pressure with an outlet diameter **24** of 6". In still other embodiments, the drain **10** is configured to flow between 375 and 425 GPM at 2 inches of head pressure with an outlet diameter **24** of 6". In still other embodiments, the drain **10** is configured to flow approximately 400 GPM at 2 inches of head pressure with an outlet diameter **24** of 6". In still other embodiments, the drain **10** is configured to flow between 1400 and 1600 GPM with an outlet diameter **24** of 6". In still other embodiments, the drain **10** is configured to flow approximately 1500 GPM with an outlet diameter **24** of 6". In still other embodiments, the drain **10** is configured to achieve 90% maximum flow at 4 inches or less of head pressure and an outlet diameter **24** of 6". In still other embodiments, the drain **10** is configured to achieve 90% maximum flow at 4.5 inches of head pressure and an outlet diameter **24** of 6".

In some embodiments, the drain **10** is configured to flow between 100 and 130 GPM at 1 inch of head pressure with an outlet diameter **24** of 8". In still other embodiments, the drain **10** is configured to flow approximately 122 GPM at 1 inch of head pressure with an outlet diameter **24** of 8". In still other embodiments, the drain **10** is configured to flow between 400 and 500 GPM at 2 inches of head pressure with an outlet diameter **24** of 8". In still other embodiments, the drain **10** is configured to flow between 420 and 480 GPM at 2 inches of head pressure with an outlet diameter **24** of 8". In still other embodiments, the drain **10** is configured to flow approximately 440 GPM at 2 inches of head pressure with an outlet diameter **24** of 8". In still other embodiments, the drain **10** is configured to flow between 2000 and 2500 GPM with an outlet diameter **24** of 8". In still other embodiments, the drain **10** is configured to flow approximately 2300 GPM with an outlet diameter **24** of 8". In still other embodiments, the drain **10** is configured to achieve 90% maximum flow at 5.5 inches or less of head pressure and an outlet diameter **24** of 8".

FIGS. 31-34 illustrate another embodiment of the drain **3010**. The drain **3010** is substantially similar to the drain **10** so only the differences will be discussed in detail herein. The drain **3010** includes one or more bosses **3500** extending axially from the underside **3504** of the base **3018** of the drain **3010**. Each boss **3500**, in turn, defines a first surface **3508** oriented substantially perpendicular to the central axis **3050** of the base **3018**, and a second surface **3512** oriented substantially perpendicular to the central axis **3050** and spaced axially from the first surface **3508**. More specifically, the second surface **3512** is positioned axially below and radially inwardly of the first surface **3508**.

As shown in FIG. 32, the first surface **3508** defines a threaded aperture **3516** configured to receive a fastener **3520** therein for coupling a connection member **3524** to the base **3018**. The second surface **3512**, in turn, defines a slot **3528** radially aligned with the aperture **3516** of the first surface

3508. Together, the aperture **3516** and the slot **3528** help radially orient the connection member **3524** relative to the base **3018** of the drain **3010** by receiving a pin **3532** or other alignment member therein. While the illustrated drain **3010** includes four bosses **3500** formed therein, in alternative embodiments more or fewer bosses **3500** may be present.

The drain **3010** also includes one or more connection members **3524** configured to releasably secure the drain **3010** to a roof **14**, alignment plate (not shown) or other support surface. Each connection member **3524** includes a first leg **3536** and a locking flange **3540**. As shown in FIG. 32, the locking flange **3540** is radially and axially offset from the first leg **3536** and configured to contact the underside of the roof **14** or support surface. While the illustrated locking flange **3540** is substantially arcuate in shape, in other embodiments the flange **3540** may include teeth, texture, protrusions, and the like as necessary to interact with the underside of the support surface or roof **14**.

As shown in FIG. 32, the first leg **3536** of the connection member **3524** defines an elongated slot **3544** sized to align with both the aperture **3516** and the slot **3528** of the boss **3500** and allow a fastener **3520** and/or pin **3532** to pass therethrough. The slot **3544** is configured to allow the connection member **3524** to be adjusted radially relative to the base **3018** during the installation process.

The drain **3010** also includes a plurality of stand-offs **3548** extending axially from the underside **3504** of the base **3018**. The stand-offs **3548** are substantially cylindrical in shape and positioned equally along the outer edge **3092** of the base **3018**. During use, the stand-offs **3548** are configured to engage the roof **14** or support surface and secure the base **3018** relative thereto.

As shown in FIG. 33, the first set of base plates **3132** of the cage **3026** of the drain **3010** include a ramped surface **3550** configured to assist the locking member **3260** to travel up and onto the top of the base plate **3132** to engage the locking ridge **3264**. More specifically, the ramped surface **3550** is formed into the base plates **3132** proximate the locking notch **3266** so that, when the user rotates the cage **3026** relative to the gravel ring **3030**, the locking **3260** travels along the surface **3550** to the upper side **3554**. This makes it easier for the user to lock the cage **3026** relative to the base **3018** and also allows for a tighter fit between the two elements **3026**, **3018** once the connection has been made.

The first set of base plate **3132** also includes a locking notch **3560** formed into the upper side **3554** of the base plate **3132**. When assembled, the locking notch **3560** substantially aligns with a corresponding aperture **3564** of the locking member **3260** such that the user may insert a fastener or pin through the aperture **3564** where it is at least partially received within the locking notch **3560** to rotational lock the cage **3026** relative to the ring **3030**.

Although the invention has been described in detail with reference to certain preferred embodiments, variations and modifications exist within the scope and spirit of one or more independent aspects of the invention as described.

The invention claimed is:

1. A roof drain comprising:
a base having a throat portion and a flange portion extending radially outwardly from the throat portion, the throat portion at least partially defining a channel therethrough, an axis, and an outlet;
a gravel guard ring coupled to the base, including a plurality of teeth, and a plurality of ring locking members, wherein a plurality of gullets are defined between the teeth; and

19

a dome releasably coupled to the base with a plurality of dome locking members, the dome including a plurality of spaced ribs extending radially outwardly from a core element and defining gaps therebetween, and a plurality of crossbars extending between and interconnecting some adjacent ribs, the crossbars are positioned such that each crossbar is not aligned with any crossbars positioned in adjacent gaps, wherein the plurality of dome locking members rotationally engage the plurality of ring locking members to releasably couple the dome to the base.

2. The roof drain of claim 1, wherein the base defines a top plane, and wherein at least one gullet of the plurality of gullets at least partially extends axially below the top plane.

3. The roof drain of claim 1, wherein the base defines a top plane, wherein the dome includes a plurality of base plates extending between at least two adjacent ribs, and wherein at least one base plate of the plurality of base plates is positioned completely axially below the top plane.

20

4. The roof drain of claim 1, wherein the channel includes an inner surface, and wherein the inner surface is substantially convex in shape.

5. The roof drain of claim 1, wherein the base includes a cutting groove.

6. The roof drain of claim 5, wherein the cutting groove is positioned radially inward of an outer diameter of the dome.

10 7. The roof drain of claim 1, wherein the base defines a top plane, and wherein the drain is capable of permitting through-flows of between 75 GPM and 150 GPM at 1 inch of head pressure measured relative to the top plane.

15 8. The roof drain of claim 1, wherein each gullet is radially aligned with a corresponding gap.

9. The roof drain of claim 1, wherein at least one gap between adjacent ribs is open at the bottom of the dome.
